GERMAN GALLO P., OF NEW YORK, N. Y.

ELECTRICAL CONNECTION

Application filed April 21, 1926. Serial No. 103,659.

This invention relates to an electrical connection.

An object of the invention is to provide a simple and efficient construction whereby a high resistance and a low resistance can be connected or joined together without the usual objectionable results.

A further object is to provide a construction which is particularly adaptable for high resistance grid leads used in radio sets to avoid the interruption of service in said devices usually due to the fact that the high and low resistance wires are directly connected.

A further object is to provide a construction which is adapted not only for fixed resistances but for variable resistances.

The invention is illustrated in the drawings, of which—

20 Figure 1 is a plan view of a variable resistance or grid leak with the spring pressure plate removed;

Figure 2 is a section on the line 2—2 of Figure 1 but showing the spring pressure plate in position;

Figure 3 is section through a fixed resistance;

Figure 4 is a section on the line 4—4 of Figure 3;

30 Figure 5 is a diagram illustrating (but not to scale) the normal and the ideal change in conductivity in such a circuit. Figure 6 similarly illustrates the change in accordance with the practical embodiment herein shown.

The form of the invention shown in the drawings is a preferred form, although it is understood that modifications in the construction and arrangement of the parts and in 40 the character of the materials used may be adopted without departing from the spirit of the invention as set forth in the appended claim.

In the use of resistances, especially high resistances where they have been connected in circuit with low resistance wires, it has been customary to connect the high resistance portion directly to a low resistance wire or contact and it has been found that when such a 50 direct connection is made that as the surface

has become corroded and as small or minute arcs are formed that the contact between the two surfaces is so greatly impaired that in a very short time the device becomes useless, especially in locations where there is considerable moisture in the air which will facilitate the corroding action.

55 I have found that these difficulties may be overcome by avoiding the abrupt transition between the high resistance and the low. The 60 type of conductor used in this high resistance has, as is well-known, frequently a value of great magnitude, and the conductivity of the connections as compared with that of the conductor is relatively very high. The difficulty referred to appears to be localized at the juncture point between these substances having such different rates of conductivity. The difficulty may be overcome by making the transition a more gradual one. Within the 70 broad scope of this invention any means of gradually increasing the conductivity may be employed. For practical purpose I have found that this may be satisfactorily accomplished by interposing between the conductor 75 and the resistance a substance having a conductivity intermediate between the two, so that there will not be such wide discrepancy between the conductivities of adjacent elements.

A practical material for this purpose has been 80 found to be the substance sold as fabricoid. The coating of this material is, to normal voltages, substantially an insulator, but as compared with the very high resistance above referred to, it is a conductor. It appears to 85 have a conductivity somewhere a mean between that of the resistance element and of the conductors, so that the transition between the highly conducting and the highly resist- 90 ant element is broken into two commensurate stages, neither one of which is of sufficient magnitude to be so objectionable. In other words the conductivity of the connector between the high and low resistance elements is graded between the conductivity of these 95 elements and the conductivity in passing from the high resistance element to the low resistance element is gradational.

100 By making this graded or gradual transition I have found, in practical experience,

that the difficulties and objections hereinbefore referred to are eliminated and that it is possible to make a resistance element embodying this principle, which is unusually 5 stable in its resistance value.

In the drawings, which show the preferred form of my invention, I provide a base 10 of insulating material on which I may dispose a strip of material such as paper 11 on 10 which a high resistance line or portion 12 is made. This line may be of ink or graphite, or of any other suitable substance having a high resistance. At one end of this high resistance line 12 I dispose a small strip or 15 layer of a material of lower resistance 13 such as fabricoid or any other suitable material I may elect to use. On this layer 13 I dispose a contact strip 14 of metal to which suitable circuit connections may be made in 20 any desired manner. At the other end of the high resistance strip I dispose a layer 15 of intermediate resistance value which may be of fabricoid or other material and on the end of this I dispose a metal contact strip 16. 25 These strips are held in place by nuts 17 and 18 and over these is disposed a pressure bar such as 19 which may be of any suitable material, this bar being in operation held in place by nuts threadably disposed on the 30 stems of screws 22 and 23. The layer 15 of intermediate resistance has its free end 24 rolled up on a stem or shaft 25 having a thumb nut 26 whereby it may be manipulated to roll up the free end of the strip 15 35 either to the right or unroll it to the left. The flow of current will be for instance from the circuit to the metal strip 16 which is of low resistance and then through the variable strip 15 of intermediate resistance, 40 through this strip to the high resistance 12 and then along the high resistance 12 to the fixed strip 13 of intermediate resistance and from this to the other contact strip 14 of intermediate resistance. It will be understood 45 that no electrical circuit is provided through the pressure bar 19 and that the electrical circuit is confined to the parts just traced; any well known form of insulation 50 may be provided to prevent passage of any of the current through the bar 19.

This construction therefore interposes between each end of the high resistance and the corresponding low resistance, contact strips, suitable layers of material of intermediate resistance and through which the current is to pass. In this particular construction the amount of high resistance in circuit is determined by the degree to which the variable portion of the intermediate 55 resistance is unrolled. The pressure bar 19, by pressing on the roll of intermediate resistance, will hold it permanently in any adjusted position.

In Figure 3 I show what is preferably a 60 glass tube set 27 having metal caps 28 and

29 on the end thereof to which contact clips 30 and 31 are fastened. These clips are adapted to embrace the end of a base 32 on which a high resistance element 33 is disposed. At each end and disposed between 70 the high resistance portion and the clips are layers such as 34, 35, 36 and 37 of resistance material of intermediate value. This particular construction is adaptable for a fixed electrical connection of the type used for fixed 75 grid leaks in radio sets. The values of the high, low and intermediate resistances can be varied at will and the character of the materials employed may be varied as desired.

It will be understood that such an electrical resistance as here contemplated is intended for use in the oscillatory portions of radio circuits, as for example, for use as a grid leak or as the resistance element of a resistance coupling. The value of resistance 80 employed varies with the use to which it is put.

In Figure 5 is shown the ideal transition between the rate of conductivity of the terminals and the rate of conductivity of the 90 high resistance. In this drawing, the ordinates are expressed in rates of conductivity, while the abscissæ represent different physical portions of the resistance unit. The extreme right and left hand positions represent the terminals and the central portion 95 represents the resistance element itself. In Figure 5, the straight vertical dotted lines at the terminal with the horizontal dotted intermediate line connecting them, show the customary form of resistance unit with its sudden and instantaneous and extreme change in conductivity. In this same figure, the solid line represents a gradual decrease in conductivity from the terminal to the resistance 100 unit and a gradual increase on the other end from the unit to the other terminal. This is the ideal situation in which no sudden change of conductivity occurs at any point.

In Figure 6, is shown the practical embodiment of the invention which is herein illustrated, in which the change between conductivity of the terminal, and conductivity of the resistance element is bridged by the intermediate resistance, so that instead of one 115 sudden large chamber, there are two smaller ones, resulting in a very great reduction in the resultant difficulties. It would be obvious that the closer the curve may be made to approach the contact line of Figure 5, the 120 greater will be the elimination of this source of trouble. The dotted line represents the present form for comparison, as shown in Fig. 5.

What I claim is:

An electrical resistance which comprises a high resistance portion, a portion of intermediate resistance value of variable length contacting therewith and a portion of low resistance value permanently fixed against 125

one end of the intermediate resistance portion, means for varying the length of contact of the intermediate resistance with the portion of high resistance, and means for holding the free end of the portion of intermediate resistance firmly against the portion of high resistance.
